UNITED STATES PATENT OFFICE.

BENJAMIN B. BETTS, OF ST. LOUIS, MISSOURI.

GUARD-RAIL.

1,155,994.

Specification of Letters Patent.

Patented Oct. 5, 1915.

Application filed March 12, 1915. Serial No. 13,941.

To all whom it may concern:

Be it known that I, BENJAMIN B. BETTS, a citizen of the United States, and resident of St. Louis, Missouri, have invented certain new and useful Improvements in Guard-Rails, of which the following is a specification containing a full, clear, and exact description, reference being had to the accompanying drawings, forming a part hereof.

10 My invention relates to improvements in guard rails, wherein the guard rail with its mounting, a mounting for a running rail, and a brace extending from the ball of the running rail to the guard rail are all formed 15 as an integral unit.

The object of my invention is to construct 20 as an integral unit, preferably a casting, a guard rail, having laterally continuous mountings for its support as well as the support of a running rail, said mountings being longitudinally spaced for drainage and 25 cleaning between the guard and running rails, a brace extending laterally from the guard rail arranged at its lowermost end to overlie the base of a running rail and its 30 uppermost end to underlie the ball of the running rail, each of said mountings having means such as spike openings to provide for securing the running rail and the mountings to the ties or sleepers. Such a guard 35 rail with its mountings and braces is capable of being handled as a unit and being placed with relation to a running rail with no fitting or adjustment of parts.

With the above objects in view, my invention 40 consists in certain novel features of construction and arrangement of parts hereinafter fully set forth, pointed out in my claims and illustrated by the accompanying drawings, in which—

Figure 1 shows in plan a guard rail, constructed according to my invention as in use in connection with a running rail; Fig. 2 is a side elevation of my guard rail as shown in 45 Fig. 1; Fig. 3 is a transverse sectional elevation taken on the line 3—3 of Fig. 2; Fig. 4 is an enlarged transverse sectional elevation taken on the line 4—4 of Fig. 1; Fig. 5 is an enlarged transverse sectional elevation showing my improved foot guard at 50 the end of the guard rail; and Fig. 6 is a longitudinal sectional elevation showing the foot guard taken on the line 6—6 of Fig. 1.

Referring by numerals to the accompanying drawings: 7 designates a running rail and 8 the ties or sleepers, both of which are

of common construction and of themselves form no part of my invention.

The numerals 9 designate plates, herein-after termed mountings, which are spaced 60 from each other so that each one will rest on one of the ties or sleepers and each mounting has near one of its ends a running rail bearing shoulder 10, a plane seat 11 for the running rail, and a spike opening 12, formed 65 through the mounting and preferably intercepting the shoulder 10.

The guard rail 13 integrally connects all 70 of said mountings and its vertical web 14 has different lateral spacings from the running rail seats on the various mountings so that the guard rail as a whole may have the usual, prescribed parallelism at its longitudinal central portion with the running rail with its ends flared or curved laterally away 75 from the running rail.

By preference the guard rail web is reduced in depth between the mountings and these reduced portions, designated 15, are each shaped or trussed between the mountings, whereby to conserve material, as well as to provide clearance between the road bed 80 and guard rail, for drainage and access to the roadbed beneath the guard rail and between the guard and running rails.

Arising from the mountings 9 are braces 16, at the base of each of which is formed a recess 17 to receive the base of the running rail, which braces incline upwardly and laterally toward the running rail and terminate 90 at a point where their upper free end will seat under the ball of the running rail. These braces shift the lateral strains on the guard rail to the running rail and prevent buckling of the mountings.

In order to lend rigidity to the guard rail 95 I resort to bracing webs 18 which integrally connect the ball and web of the guard rail with the mounting, and, in order to lend rigidity to the braces 16 I form between 100 these braces and the web of the guard rail ribs 19.

Formed through each mounting outside the guard rail are the spike openings 20, whereby to secure the mountings to the ties.

Between the pairs of mountings at each end of the guard rail at the points where the guard rails curve outwardly from the running rail I arrange a guard 21 to prevent the catching and holding of the feet of 110 trackmen or other persons between the running rail and the flared ends of the guard

5 rail. This guard 21 comprises a plate whose body portion is substantially horizontal and occupies a position between the guard rail and running rail, its one side margin being integrally connected with the web of the guard rail and its opposite side margin extending to the running rail. The one end margin of this plate is integrally connected with the brace 16 of the one 10 mounting, while its other end margin is integrally connected with the body of the next adjacent mounting, this last mentioned end of the plate being curved downwardly to obviate the catching of loose hanging parts 15 on rolling stock.

Having thus described my invention, what I claim as new therein and desire to secure by Letters Patent of the United States therefor, is:

- 20 1. A guard rail structure comprising a plurality of spaced tie plates, a guard rail whose web integrally connects the tie plates, a brace on certain of the tie plates extending upwardly and laterally away from the 25 guard rail over the tie plates, a shoulder on each plate, each plate having spike openings therethrough and each brace having a recess at its base in opposition to one of said shoulders and constituting a holding seat for one 30 flange of the running rail.
2. A guard rail structure cast complete in one piece and comprising a plurality of tie plates, a guard rail whose web connects the tie plates, said plates extending on both 35 sides from said web and having near their

ends spike openings, a brace over each plate rising from the base of the web of the guard rail and inclining upwardly away from said web, ribs between said web and said braces, bracing webs between the guard rail web 40 and the plates opposite said ribs, there being a recess at the base of each brace constituting a holding seat for one flange of the running rail and a shoulder on each plate in opposition to each recess adapted to bear 45 against and hold the other flange of the running rail.

3. In combination with a guard rail, a plurality of mountings formed integrally with the guard rail and extended laterally 50 therefrom to receive a running rail, an upwardly and laterally inclined brace over each plate and connected with said web, each brace having a recess at its bottom to receive the base of a running rail, a shoulder on 55 each plate in opposition to each recess, there being spike openings through said plates whereby to secure the plates to sleepers and to secure the running rails by spiking and foot guards integrally connecting the end 60 pairs of said plates with the web of the guard rail.

In testimony whereof, I have signed my name to this specification, in the presence of two subscribing witnesses.

BENJAMIN B. BETTS.
